DESIGN FOR A DRESS

Johnnye Lee Caston, Chicago, Ill., assignor to
The Sterling Company, Chicago, Ill., a corporation of West Virginia

Application November 23, 1933. Serial No. 49,829

Term of patent 3½ years

To all whom it may concern:

Be it known that I, JOHNNYE LEE CASTON, a citizen of the United States, residing at Chicago, in the county of Cook and State of Illinois, have invention a new, original, and ornamental Design for a Dress, of which the following is a specification, reference being had to the accompanying drawing forming a part thereof.

Fig. 1 is a perspective front view of a dress embodying my design; and

Fig. 2 is a perspective view in contour of the rear of the dress shown in Fig. 1, it being understood that the materials of the body and collar portions have the respective patterns illustrated in Fig. 1.

I claim:

The ornamental design for the dress as shown and described.

In witness whereof, I hereunto subscribe my name this 21st day of November, 1933, at Chicago, Illinois.

JOHNNYE LEE CASTON.
